DESIGN FOR A POCKET TOOTHBRUSH OR SIMILAR ARTICLE

Lyle E. Fry, Los Angeles, and Raymond D.
Champion, San Gabriel, Calif.

Application August 29, 1942, Serial No. 108,070

Term of patent 14 years

To all whom it may concern:

Be it known that we, Lyle E. Fry and Raymond D. Champion, citizens of the United States and residents, respectively, of Los Angeles and San Gabriel, in the county of Los Angeles and State of California, have invented a new, original, and ornamental Design for a Pocket Toothbrush or Similar Article of which the following is a specification, reference being had to the accompanying drawing, forming a part thereof.

Referring to the drawing:

We claim:

The ornamental design for a pocket toothbrush or similar article, substantially as shown.
